UNITED STATES PATENT OFFICE.

WILLIAM E. VAN SYOC, OF PUEBLO, COLORADO, ASSIGNOR OF ONE-HALF TO PERRY H. STREETER, OF PUEBLO, COLORADO.

STOVE.

1,218,913.

Specification of Letters Patent.

Patented Mar. 13, 1917.

Application filed April 27, 1914, Serial No. 834,736. Renewed August 9, 1916. Serial No. 114,073.

To all whom it may concern:

Be it known that I, WILLIAM E. VAN SYOC, a citizen of the United States, residing at Pueblo, in the county of Pueblo and State of Colorado, have invented a certain new and useful Improvement in Stoves, of which the following is a full, clear, and exact description.

This invention is an improvement in 10 stoves and relates in particular to stoves adapted to the burning of refuse, peat, lignite, slack and other low grade fuels, though wood or coal may be employed in it.

The principal objects of my invention are 15 the provision of a stove which shall be simple and economical to construct, which shall have the maximum of radiating surface particularly in the lower portion thereof, and which shall be provided with means for indicating the amount of fuel remaining in the 20 fuel chamber. Further objects and advantages of my invention will later appear in this specification.

In the single sheet of drawings accompanying this application and forming a part hereof—

Figure 1 is a perspective view of a stove embodying my invention, a part of the front being broken away to disclose the inner parts 30 of the stove;

Fig. 2 is a front elevation of the stove shown in Fig. 1; and

Fig. 3 is a horizontal section through the body portion of the stove, showing the deflector in plan view.

The reference numeral 10 indicates a base which, in the preferred form shown in the drawings, is of a general circular form but provided at suitable intervals with semi-circular projections 11 to accommodate similarly formed portions on the stove body, as will be later described. Legs 12 support the base a suitable distance above the floor and 13 indicates the usual ash pan. The base is 40 provided with an opening 14, one being shown though any convenient number may be employed, which opening is adapted to be closed by a slide 15 extending to the front of the stove where it can be conveniently manipulated. This opening 14 is for the double purpose of permitting the ash to be discharged into the ash pan and for admitting added draft if desired.

The body portion 16 of the stove is also 55 of a general circular cross section and is of

a size to snugly fit within a bead 17 near the edge of the base. A plurality of flues 18, in this case shown as five though any convenient number may be employed, are formed as semicircular corrugations of the metal of 60 which the body portion is made, these corrugations fitting within the projections 11 on the base. The metal of the body portion is preferably shaped with slight offsets 19 adjacent each flue corrugation, these offsets being of a depth equal to the thickness of the metal. Flue closure plates 20, preferably curved on the same curvature as that given the body, lie within the offsets 19 and are riveted to the body portion; these closure 70 plates extend to within a few inches of the bottoms of the corrugations, as indicated at 21 in Fig. 1, thus leaving the flues open below that point. Dampers 22 are provided in each of the flues for controlling the draft 75 allowed the fire.

A cover 23, preferably dome shaped as shown, closes the body portion at the top. Flue continuations 24 are formed in the cover in manner like the flues 18, these continuations being located to match on to the flues 18. A pipe connection 25 at the top opens into each flue continuation and also into the top of the stove.

I prefer to employ a plate 26 (though this 85 element may be omitted and the remaining features of my invention employed alone if desired) which rests on the fuel and from which a rod 27 projects through an opening in the cover 23. This plate performs two 90 functions: it serves to compress the fuel and to prevent draft therethrough. The rod extending out through the top of the stove forms a convenient means for handling the plate and also serves as an indicator to 95 show the amount of fuel remaining in the stove and when recharging is necessary.

A deflector 28, preferably in the shape of a frustum of a cone as shown, is provided adjacent the bottom of the stove but spaced 100 therefrom a short distance by legs 29. This deflector, which is imperforate, fits closely to the body portion at its top but, on account of its frusto-conical shape, is spaced therefrom a short distance at its bottom. The bottom 21 of the flue closure plate 20 is located intermediate the top and bottom of the deflector 28.

A draft door 30 is located adjacent the bottom of the body portion and I may, if 110

desired, place a charging door 31 at a point near the top of the body portion.

Operation.

5 When the stove is to be charged with refuse or the like a sliding section 32 of the stove pipe 33 is raised and the cover 23 and the indicator plate 26 removed. The stove, being principally of sheet iron and therefore very light may, if desired be carried 10 out of the house for charging; or it may be filled in place if preferred. When it has been filled the plate 26 and the cover 23 are replaced and the section 32 slid down 15 to close the stack. The fire is then lighted through the door 30 and a good draft allowed for starting, the plate 15 being withdrawn if necessary for this purpose. The blaze in the refuse will quickly spread and 20 as ignition becomes general the products of combustion will pass down under the deflector 28 and, circulating within the space between the deflector and the body, will pass out through the nearest flue. As the 25 charge in the stove is burned the plate 26 will lower and the amount which the rod 27 projects above the cover will apprise one of the amount of fuel remaining in the stove. If higher grade fuel, such as wood 30 or coal, is to be burned it may be charged through the door 31, the plate 26 having first been lifted.

Increased radiation surface is provided by my stove in two ways. First: the flues 35 18 where the hot gases pass out and where the principal heating effect is produced in stoves of this character, are on the outside of the stove. Second: the gases in circulating throughout the space between the 40 body and the deflector heat the entire circumference of the stove in that portion and thus furnish more heat in the place where it is most desired—near the floor. Furthermore, access to the flues is made easier for 45 the gases, the fuel being held away from the flue openings and the gases having a path out at every point in the circle.

In case the plate 26 is omitted, the con-

tinuation of the flues by the passages 24 in the cover is important as the hot gases are 50 thereby prevented from igniting the fuel in the top of the stove, it being desirable in stoves of this sort to have the fire all in the bottom.

Having thus described my invention, what 55 I claim and desire to secure by Letters Patent is:

1. In a stove, a body portion having a tubular interior and a plurality of flues on the exterior thereof, and an imperforate, 60 frusto-conical deflector spaced above the bottom of said body portion, said flues being open to the body portion from the bottom to a point intermediate the top and bottom of said deflector.

2. In a stove, a body portion having a tubular interior and a plurality of flues on the exterior thereof, and a cover for said body portion also having a plurality of flues on the exterior thereof, the flues on 70 the cover being so placed as to form continuations of the flues on the body portion.

3. In a stove, a body portion having a plurality of flues communicating with its interior adjacent the bottom thereof but 75 closed from said body portion throughout the remainder of their length, and an inclined, imperforate deflector within said body portion and extending over said flue openings.

4. In a stove, a base, a body portion having a plurality of flues communicating with its interior adjacent the bottom thereof but closed from said body portion throughout the remainder of their length, and an inclined, imperforate deflector supported on 85 said base but spaced therefrom, said deflector extending over said flue openings.

In testimony whereof, I have hereunto affixed my signature in the presence of two 90 witnesses.

WILLIAM E. VAN SYOC.
